[57] CLAIM

The ornamental design for a vehicle loading ramp, as shown and described.

DESCRIPTION

FIG. 1 is a perspective view of the vehicle loading ramp showing my new design with the broken line showing of a truck and an adjacent ramp disclosed for illustrative purposes only and forming no part of the claimed design;

FIG. 2 is a side elevational view with the opposite side being a mirror image thereof and with the broken lines shown for illustrative purposes only and forming no part of the claimed design;

FIG. 3 is a front elevational view thereof;

FIG. 4 is a rear elevational view thereof;

FIG. 5 is a top plan view thereof;

FIG. 6 is a bottom plan view thereof.
